UNITED STATES PATENT OFFICE.

JEPTHA GIDEON HOLLINGSWORTH, OF KANSAS CITY, MISSOURI, ASSIGNOR
TO THE S. S. WHITE DENTAL MANUFACTURING COMPANY, OF PHILA-
DELPHIA, PENNSYLVANIA.

DESIGN FOR A DENTIST'S DIE-PLATE.

SPECIFICATION forming part of Design No. 25,029, dated December 31, 1895.

Application filed November 1, 1895. Serial No. 567,653. Term of patent 14 years.

To all whom it may concern:

Be it known that I, JEPHTA GIDEON HOLLINGSWORTH, of Kansas City, Jackson county, in the State of Missouri, have invented a new and useful Design for Dentists' Metallic Die-Plates for Artificial Crowns or Caps and Facings for Teeth, of which the following is a specification, reference being had to the accompanying drawing, forming part thereof, o and which represents a plan view of my newly-invented design.

The leading features of my invention consist of a die-plate having upon one side of its center the dies for crowns or caps and facings for teeth of the right side of the human jaw, with the dies for crowns or caps and facings for teeth of the left side of the jaw upon the other side of the center of the plate, and having separately grouped in right and left divisions the dies intended, respectively, for the caps or crowns for superior molars, for inferior molars, for superior bicuspid, and for inferior bicuspid, and having similarly grouped the dies intended, respectively, for the facings for superior molars, for inferior molars, for superior bicuspid and for inferior bicuspid.

In the drawing, A is the die-plate, and B and C the right and left divisions of the female dies of the group for caps or crowns for superior molars for the right and left sides, respectively.

D is the right division and E the left divis-

ion of female dies of the group for caps or crowns for inferior molars.

F and G indicate, respectively, the divisions of the group of female dies for caps or crowns for superior bicuspid of right and left sides; and H the right division, and I the left division of the group of female dies for caps or crowns for inferior bicuspid for the right 40 and left sides, respectively.

J and K are the right and left divisions of the group of female dies for facings for superior molars of the right and left sides.

L is the right division and M the left division of the female dies of the group for facings for inferior molars of the right and left sides, respectively.

N and O are the right and left divisions of the group of female dies for facings for the 50 right and left side superior bicuspid, and P and Q the right and left divisions of the group of female dies for facings for inferior bicuspid of the right side and left side.

I claim as my invention—

The design for a dentist's die-plate, substantially as shown and described.

In testimony whereof I affix my signature in presence of two witnesses.

JEPHTA GIDEON HOLLINGSWORTH.
